UNITED STATES PATENT OFFICE.

GEORGE L. McCAIN, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,312,555.

Specification of Letters Patent. Patented Aug. 12, 1919.

Application filed November 12, 1915. Serial No. 61,066.

To all whom it may concern:

Be it known that I, GEORGE L. McCAIN, a citizen of the United States, and resident of Detroit, Wayne county, State of Michigan, have invented certain new and useful Improvements in Hydrocarbon-Motors, of which the following is a specification.

This invention relates to hydrocarbon motors, and particularly to motors for aero-plane use.

One of the objects of the invention is to provide a hydrocarbon motor of high power with a suitable propeller driving mechanism associated therewith.

Another object of the invention is to provide a hydrocarbon motor with a propeller driving mechanism and a cam shaft driving mechanism.

Another object of the invention is to provide a hydrocarbon motor with suitable bearings within the crank case of the motor for carrying the driving shaft of an aeroplane propeller.

Other objects of the invention will appear from the following description, taken in connection with the drawings which forms a part of this specification, and in which—

Figure 1 is a vertical longitudinal section through a motor embodying this invention; Fig. 2 is a transverse vertical section through the motor shown in Fig. 1; and

Fig. 3 is a plan view of part of the motor shown in Figs. 1 and 2.

Referring to the drawings, 10 represents the upper half and 11 the lower half of the motor crank case or base, between which halves are the bearings 12 for the crank shaft 13. At one end of the motor, the crank shaft extends through the crank case, and on its projecting end 14 is mounted a fly-wheel 15.

The lower half 11 of the crank case forms an oil well, which is provided with an oil screen 16 extending entirely across the well.

The oiling system may be completed by the use of a suitable pump and conduit to carry the oil from the well below the screen 16 to the various bearings to be lubricated.

The form of motor shown is of the V-type, the cylinder blocks 17 being mounted as shown particularly in Fig. 2, upon the upper half 10 of the crank case. Suitable connecting rods 18 and pistons 19 are provided.

Extending along the heads of the motor 55 cylinders are cam shafts 20, one for each side of the motor, and suitable cams are arranged on these shafts for operating the intake and exhaust valves 21 and 22 respectively. Rock arms 23 are included in the 60 valve operating mechanism, and suitable intake and exhaust pipes 24 and 25 supply the gases to and exhaust them from the motor cylinders. A carburetor 26 supplies the intake conduits.

The end of the motor crank shaft 13 opposite to that upon which the flywheel 15 is mounted, is provided with a gear or sprocket 27 which may be connected to drive the various auxiliary mechanisms of the motor, such 70 as the pump, generator, etc.

The motor herein illustrated is particularly adapted for aeroplane work, and it is provided with a heavy driving shaft 29, which is connected directly to drive a propeller 30, which is securely keyed to the driving shaft at the end of the motor opposite to that where the fly-wheel 15 is mounted. For the purpose of procuring steadiness in the drive, and reducing torsion on the crank 80 shaft 29 from the crank shaft is provided at the end of the motor adjacent the fly-wheel 15. As shown, this gearing consists of a pair of spur or similar gears 31 and 32, the 85 former being secured to the crank shaft and the latter to the driving shaft 29.

The driving shaft 29 is shown as mounted in bearings 33 in the upper part of the crank case upper half 10, these bearings being exposed to the interior of the crank case so that they will be lubricated by the splash therein or may be fed by conduits in the lubricating system and the overflow of oil drained back into the crank case. Thus is obtained a rigid 90 and secure mounting for these bearings 33, and the driving shaft 29 is maintained in correct alignment in its parallel and offset relation to the crank shaft.

The upper halves of the bearings 33 are 100 retained in place by a cover 34, which extends the length of the motor crank case and closes an opening in its upper wall, between the bases of the cylinder blocks 17. This cover is secured in place by bolts, and 105 by removing it, the entire driving shaft 29 may be lifted out.

The drive for the cam shafts 20 at the

heads of the motor cylinders is taken from the driving shaft 29. A suitable worm gear 35 is mounted at about the middle of the driving shaft 29, and a shaft 36 for each side of the motor carries the drive to the cam shafts through gears 37 and 38 at the respective ends of the shafts 36. The lower ends of the shafts 36 extend into the crank case as shown particularly in Fig. 2, where they receive ample lubrication, and their upper ends and the gears 38 on those ends are housed within a casing 39, which is suitably secured to the upper ends of the cylinders.

15 While one form only of the invention has been shown and described it will be understood that the invention is not limited to this form, as it will be apparent that changes may be made without departing from the 20 spirit or scope of the invention as set forth in the accompanying claims.

Having thus described my invention, what I claim and desire to secure by Letters Patent is:—

25 1. The combination with a V-type motor having a crank shaft, of a fly wheel on said shaft at one end of the motor, a driving shaft arranged parallel to and in the same vertical plane with the crank shaft and 30 above the latter, gearing from the crank shaft to the driving shaft at the fly wheel end of the motor and a propeller on the driving shaft at the other end of the motor.

2. The combination with a multi-cylinder

35 V-type motor having a crank shaft, of a driving shaft extending the full length of the motor and arranged parallel to and offset from the crank shaft and connected to be driven thereby, cam shafts extending 40 along the heads of the motor cylinders, gearing from the driving shaft to said cam shafts, and a propeller mounted on the driving shaft.

3. The combination with a multi-cylinder

45 V-type motor having a crank shaft, of a driving shaft arranged parallel to and offset from the crank shaft, gearing at one end of the motor connecting the crank and driving shafts, a propeller mounted on the driving shaft at the other end of the motor, cam shafts above the driving shaft and extending along the heads of the motor cylinders, and gearing from the driving shaft to

the cam shafts intermediate the ends of the motor.

55

4. The combination with a V-type motor having a crank shaft, a flywheel at one end of said crank shaft, a gear sprocket at the other end of said crank shaft, a driving shaft parallel to said crank shaft and extending the length of the motor, gearing between said crank shaft and said driving shaft and a propeller at one end of said driving shaft.

5. The combination with a multi-cylinder 65 motor having a crank shaft, of a driving shaft parallel thereto and above the same in the same vertical plane therewith and extending the full length of the motor, a cam shaft extending along the heads of the 70 motor and for the full length of the latter and parallel to the first mentioned shaft, and gearing for transmitting motion from the crank shaft to the driving shaft and separate gearing for transmitting motion 75 from the driving shaft to the cam shaft.

6. The combination with a V-type motor having a crank shaft, of a driving shaft extending the full length of the motor and arranged parallel to and offset from the 80 crank shaft and connected to be driven thereby, cam shafts above said driving shaft and extending along the heads of the motor cylinders, a gear at about the middle of said driving shaft and connection from said 85 gear to both said cam shafts for operating the same.

7. The combination with a V-type motor having a crank shaft, of a driving shaft arranged parallel to and above the crank 90 shaft and in the same vertical plane therewith said driving shaft extending the full length of the motor through the upper part of the crank case, gearing at one end of the motor driving the driving shaft from the 95 crank shaft, cam shafts extending along the motor for the full length thereof above the driving shaft, a gear substantially midway of the driving shaft, connecting shafts between said cam shafts and said driving 100 shaft, and gears carried at the lower ends of said connecting shafts within the crank case for engaging said central driving shaft gear.

In testimony whereof I affix my signature. 105
GEORGE L. McCAIN.
